OIL-TANK CLEANER.

Application filed May 18, 1925. Serial No. 31,187.

This invention relates to attachments to or accessories for use in connection with oil tanks and the like and has for its object the provision of a novel device designed to be mounted within an oil or other tank and capable of operation by a single individual from the top thereof whereby to clean out any accumulations of sediment or other matter which would impair the quality of the product stored within the tank.

It is well known that in oil tanks there is a heavy accumulation of basic sediment formed within a comparatively short time and which must be removed occasionally to avoid impairing the quality of oil, gasoline or the like. The ordinary method of effecting cleaning out the tank is for several workmen to enter the tank and clean it out manually. This operation is a dangerous one owing to the existence of poisonous and deadly gases which accumulate within the tank and it frequently occurs that the workmen are overcome and are perhaps seriously and permanently injured as the result of inhaling the obnoxious gases.

It is with these facts in view that we have designed the present device which is intended to be mounted permanently within a tank and which is capable of operation at any desired time for the purpose of sweeping out the accumulation of sediment, only one operator being necessary and he being stationed at the top of the tank and never needing to enter and be exposed to the dangers of the deadly gases.

An important object is the provision of a device of this character which is so constructed and arranged that a power mechanism may be applied thereto at any desired time for effecting the actual sweeping out.

An additional object is the provision of a device of this character which will be simple and inexpensive in manufacture, easy to install and operate, positive in action, efficient and durable in use, and a general improvement in the art.

With the above and other objects and advantages in view, the invention consists in the details of construction to be hereinafter more fully described and claimed, and illustrated in the accompanying drawings in which:

Figure 1 is a vertical cross section taken

through an oil tank showing our invention in applied position, 55

Figure 2 is a horizontal section through the tank taken substantially on the line 2—2 of Figure 1,

Figure 3 is a detail plan view of the driving mechanism at the top of the tank, 60

Figure 4 is a detail perspective view of one end of the sweep,

Figure 5 is an enlarged detail section showing the mounting of the main shaft at the top of the tank, 65

Referring more particularly to the drawings, the letter A represents a tank intended for the storage of oil or any other liquid, which tank is provided with an outlet opening B at its lower portion, and at opposite 70 sides of which we prefer to locate stops 10 and 11 which are for a purpose to be described.

Mounted at the center at the bottom of the tank is a suitable step or other bearing 75 12 for the lower end of a vertical operating shaft 13 which has its upper end engaged through a bearing 14 forming part of a spider 15 carried by a plurality of bars 16 secured within the upper portion of the 80 tank. The shaft 13 is of such length that its upper end terminates below the top of the manhole C and this upper end is squared or otherwise formed into angular shape as indicated at 17 for a purpose to be described. 85

Secured upon the lower portion of the shaft 13 is an elongated arm or wing 18 which might be held in place by any desired means but which is here shown as formed or provided with mating clamping members 19 embracingly engaging the shaft 13 and secured together as for instance by means of suitable rivets 20 or the like. To make the structure more stable, a securing element such as a pin 21 is also passed 90 through the shaft 13 in addition to passing through the wing or arm. Secured to and depending from this wing or arm 18, which is preferably formed of metal, is a wiper 22

necessarily formed of some suitable flexible 100 material such as sheet rubber, canvas ducking or the like. The lower edge of this flexible material is designed to bear upon the bottom of the tank while the outer end 23 is intended to bear against the inner wall 105 of the tank near the bottom thereof. In

order to brace the wing or arm use may be made of a stay rod or the like which is indicated at 24 and which is connected with a collar 25 secured on the shaft 13 beneath the bearing 14. Any necessary adjustment may be made owing to the provision of a turn buckle 26 which is interposed in the rod 24 as clearly shown.

Cooperating with the movable sweep or wing is a deflector or guide 27 which may be formed of wood or metal and which may in actual practice be simply an elongated board of suitable height pivoted at one end upon the lower portion of the shaft 13 and having its other end terminating adjacent the inner periphery of the tank wall and capable of moving between the stops 10 and 11 above described. The purpose of this guide member is to conduct the sediment or other matter swept out and collected by the wiper to the opening B so that it will be discharged in an obvious manner.

In order that the shaft 13 may be turned for operating the wiper or wing, we provide a frame structure 28 mounted on suitable legs 29 arranged in straddling relation to the manhole C and riveted or otherwise secured to the top of the tank. This member 28 is provided with a lateral extension 30 having bearings 31 thereon through which is journaled a shaft 32 carrying a worm 33 meshing with a worm wheel 34 carried by an extension shaft 35 which has a socketed lower end 36 engageable upon the squared extension 17 at the top of the main shaft 13.

In the operation of the device, it will be seen that whenever it is desired or necessary to clean out any accumulation of matter within the tank, whatever closure means is provided for the clean out opening B must necessarily be removed. The manhole cover, not shown, is likewise removed and the worm and wormwheel assembly are placed in position with the extension shaft 35 thereof engaged upon the squared upper end 17 of the shaft 13. When the shaft 32 carrying the worm 33 is subsequently rotated, as for instance by means of the crank handle illustrated at 37 it is obvious that the rotation of the worm wheel 34 secured to the shaft 35 will result in rotation of the shaft 13 carrying the wing or arm 18. As the shaft 13 is turned, the sweep 18 is carried around with it and the flexible member 22 engaging upon the bottom of the tank will operate to sweep in advance of it all accumulations of sediment or the like. This matter moved along in advance of the arm or sweep will be brought to the deflector or guide plate 27 and be directed thereby out through the discharge opening B. It makes no difference as to the direction in which the shaft 13 is turned inasmuch as the sweep or wing is capable of moving in either direction. However, when the shaft

13 is turned one way the guide plate member 27 will move into engagement with the stop 11 whereas when the sweep is moved in the other direction the guide or deflector plate will engage against the stop 10.

When the tank has been cleaned out and use of the mechanism is no longer needed, the gearing assembly is simply removed along with its shaft 35 subsequently to which any suitable cover, not shown, may be applied to the manhole. In the case of small tanks, a socket wrench may be used for turning the shaft 13 instead of providing the gear mechanism.

From the foregoing description and a study of the drawings, it will be apparent that we have thus provided a simply constructed, inexpensive and very easily installed clean-out mechanism which may remain permanently associated with a tank ready for instant use and which has the great advantage of being power operated from the outside of the tank so as to make it entirely unnecessary for a workman to enter the tank and be exposed to the dangers existing on account of the formation of gases.

While we have shown and described the preferred embodiment of the invention, it should be understood that we reserve the right to make such changes in the form, construction and arrangement of parts as will not depart from the spirit of the invention or the scope of the subjoined claims.

Having thus described the invention, we claim:

1. In combination with a tank, a clean out device comprising a vertical shaft rotatably mounted within the tank at the center thereof, a rigid sweep arm carried by the shaft, a member of flexible material carried by the sweep arm and bearing upon the bottom and against the inside wall of the tank, the tank having its lower portion provided with a discharge opening, a movable deflecting member disposable automatically at either side of the opening, and means for rotating the shaft carrying the sweep.

2. In combination with a tank, a clean-out device comprising a vertical shaft rotatably mounted within the tank at the center thereof, a rigid sweep arm carried by the shaft, a member of flexible material carried by the sweep arm and bearing upon the bottom and against the side wall of the tank, the tank having its lower portion provided with a discharge opening, a movable deflecting member disposable automatically at either side of the opening, and means for rotating the shaft carrying the sweep, said means comprising a gear assembly including a frame, an extension shaft journaled therein and formed for connection with said first named shaft, a worm wheel on the ex-

tension shaft, and a shaft journaled within said frame and carrying a worm meshing with said worm wheel.

3. A tank clean-out device comprising a vertical shaft journally mounted at the center of a tank, bearing means at the top and bottom of the tank for supporting the shaft, a sweep carried by the shaft and including a rigid arm having flexible material secured thereto bearing against the bottom and against the inside wall of the tank, mechanically operated means adapted for connection with said shaft for effecting rotation thereof, the lower portion of the tank having a clean out opening, and means for advance of the sweep for guiding an accumulation out through said opening.
4. A tank clean-out device comprising a vertical shaft journally mounted at the center of a tank, bearing means at the top and bottom of the tank for supporting the

shaft, a sweep carried by the shaft and including a rigid arm having flexible material secured thereto and bearing upon the bottom and against the inside wall of the tank, 25 mechanically operated means adapted for connection with said shaft for effecting rotation thereof, the lower portion of the tank having a clean out opening, and means for guiding an accumulation in advance of the 30 sweep out through said opening, said means comprising a deflector member pivotally mounted on the lower end of the shaft and movable across said opening, and stop means at both sides of the openings selectively engageable by said deflector member 35 for limiting its movement.

In testimony whereof we affix our signatures.

METCALFE C. COLEMAN.
EARL D. SHOEMAKER.
